UNITED STATES PATENT OFFICE.

FREDRICK CARLSON, OF NORTH EASTON, MASSACHUSETTS.

SPARK-PLUG.

1,208,479.

Specification of Letters Patent. Patented Dec. 12, 1916.

Application filed February 7, 1916. Serial No. 76,659.

To all whom it may concern:

Be it known that I, FREDRICK CARLSON, a citizen of the United States, residing at North Easton, in the county of Bristol and 5 State of Massachusetts, have invented certain new and useful Improvements in Spark Plugs; and I do declare the following to be a full, clear, and exact description of the invention, such as will enable others skilled 10 in the art to which it appertains to make and use the same.

This invention relates to new and useful improvements in spark plugs, and the primary object of the invention is to provide 15 a spark plug that will be found very efficient in operation, and also which is provided with an electrode that is self cleaning and will not become in any way choked during the operation of the plug.

20 A further object of the invention is to provide a device of this character which is simple and durable in construction, inexpensive to manufacture, and one which will be very efficient in operation.

25 With these and numerous other objects in view, my invention consists of the novel features of construction, combination and arrangement of parts which will herein be referred to and more particularly pointed out 30 in the specification and claim.

In the accompanying drawing: Figure 1 is a central vertical section of my improved 35 spark plug; Fig. 2 is a central vertical section of the plug showing the electrode and core in elevation; Fig. 3 is a detail elevation of the core and electrode removed from the plug; and Fig. 4 is a bottom plan view of the plug.

40 In the general construction of my spark plug, the main parts are similar to those commonly used in devices of this character, and they comprise an outer shell or casing 1 which has its lower end 2 externally threaded as shown at 3, so that the same 45 may be screwed into the engine cylinder. Within the lower end 2 of the casing 1 is formed a gas chamber A, for a purpose to be hereinafter more fully described. A suitable insulating core 4 preferably made of 50 porcelain, and having an annular enlargement 5 intermediate its ends, is adapted to be positioned in the casing 1, the enlargement of the same being positioned on an internal shoulder 6 in said casing. The core 4 is held in place by a retaining nut 7 as clearly shown in Fig. 1 of the drawing. The

central insulating core 4 has its upper end projecting from the casing 1 as is common in devices of this character, while the lower end 8 of the same is contracted, and is terminated a predetermined distance above the lower edge of the casing in the gas chamber A.

The insulating core 4 is provided with a central longitudinally extending electrode 65 rod 9 which extends therethrough and projects from the same at either end. A metallic cap 10 and binding nut 11 are screwed onto the upper end of the rod for the usual purposes, while the lower projecting end of 70 said rod which is designated by the numeral 12 extends from the core within the chamber A to a point adjacent the lower end of the same. Surrounding the rod 12 at the lower end of the core 4 is a steel washer 13 75 which will protect the terminal of the lower end 8 of the core. Positioned on the projecting lower end 12 of the rod 9 is a steel, substantially frusto-conical shaped electrode 14, which has its upper flat top positioned 80 against the bottom of the washer 13, while the sloping wall 15 of the same projects downwardly until it terminates at the outer edge 16 of the base 17, which is disposed adjacent the lower end of the casing. The base 17 is rounded and has its annular outer edge 16 when in position, spaced equi-distant 85 from the lower end of the casing 1. The upper flat top of the electrode is of a diameter equal to the diameter of the washer 13 90 and when positioned against the lower surface of the same, its outer edge will be disposed in alignment with the outer edge of said washer. This washer 13, owing to the 95 fact that it is of a size corresponding to the lower extremity of the core 4 against which it is positioned, has its outer edge alining with the circumference of the lower end of the core, so that when assembled, these parts 100 will be all positioned in a single arc as clearly shown in Figs. 1, 2 and 3 of the drawing.

When the parts of this plug are assembled and the frusto-conical shaped electrode is positioned against the lower end of the core 4 within the gas chamber A, it will be noticed that the extreme outer edge 16 of the same will be positioned a short distance from the lower edge of the casing, thereby forming a circular communicating passage 105 between the chamber A and the cylinder which is designated by the letter X.

When this device is in operation, the spark will jump from the edge 16 of the electrode to the adjacent portion of the lower edge of the casing, and a large circular spark will be created by this gap which will be ample for any purpose to which this plug may be used. As soon as the spark ignites the charge in the cylinder, an explosion will take place in the gas chamber A, and the discharge of the expanded gases through the communicating passage that is formed by the spark gap at X, will prevent any accumulation of carbon deposits on the wall of the electrode by preventing the adhesion of lubricating oil and subsequent carbon deposited thereon due to the burning of such oils. This operation will make my improved spark plug self-cleaning and will also prevent the same becoming choked up and stopped during its operation. This operation forms one of the most essential features of this invention, and the same is brought about by the peculiar construction of the electrode, that is so connected with the lower contracted end of the core that an arc is formed thereby which upon explosion in the gas chamber will direct all of the gases downwardly with full force against the sloping wall of the electrode. This brings about the self-cleaning action that will always keep the point adjacent the spark plug free from carbon.

From the foregoing description of the construction of my improved spark plug, the manner of applying the same to use and the operation thereof will be readily understood, and it will be seen that I have provided simple, inexpensive, and efficient means for carrying out the objects of this invention.

I claim as my invention:

A spark plug comprising a casing having an enlarged cup-shaped gas chamber formed

in its lower end, said chamber having an opening in its upper end larger than the open lower end of the same, a continuous uninterrupted downwardly beveled edge at said lower end of the chamber, an insulating core in the casing with its lower end extending downwardly in the gas chamber through the open upper end to form an annular chamber therein, said lower end of the core being arcuately contracted and terminating a short distance from the lower edge of said chamber, a centrally disposed electrode rod in the core extending from the lower end thereof, a washer on the lower end of said rod, a substantially frusto-conical shaped electrode in the lower end of said rod having a flat top engaging said washer and its lower edge spaced equi-distant from the upper portion of the outwardly beveled lower edge of the gas chamber to form a spark gap therebetween, the wall of said electrode being arcuately curved and merging at its upper edge into the arcuately contracted lower end of the core to increase the area of the annular gas chamber at that point, and the lower power of the wall of said electrode being inclined outwardly at substantially the same inclination as the beveled edge of the gas chamber, whereby upon explosion of the gases in the chamber they will be directed downwardly with full force against the wall of the electrode and hence out through the spark gap which will keep the said gap free from carbon.

In testimony whereof I have hereunto set my hand in presence of two subscribing witnesses.

FREDRICK CARLSON.
